UNITED STATES PATENT OFFICE.

EDWARD L. BERTHOUD, OF GOLDEN, COLORADO.

SIGHT FOR FIRE-ARMS.

SPECIFICATION forming part of Letters Patent No. 298,659, dated May 13, 1884.

Application filed November 24, 1883. (No model.)

To all whom it may concern:

Be it known that I, EDWARD L. BERTHOUD, a citizen of the United States, residing at Golden, in the county of Jefferson and State 5 of Colorado, have invented new and useful Improvements in Gun and Cannon Sights, of which the following is a specification.

The object of this invention is to convert a "stadias" into a rifle or common sight, where- 10 by it is adapted to ranges of from one hundred to three thousand yards; also, to provide a novel method of arranging rear and front sights upon a rifle or cannon, whereby the stadias-sight is rendered more available and 15 certain. These objects I accomplish in the manner hereinafter described and claimed, and illustrated in the accompanying drawings, in which—

Figure 1 is a cross sectional view of a rifle- 20 barrel provided with a stadias-sight according to my invention; Fig. 2, a plan or top view of a rifle on a small scale provided with my invention; Fig. 3, a side elevation of the same; Fig. 4, a sectional view on the line $x-x$ of Fig. 25 2, and Fig. 5 a sectional view on the line $y-y$ of Fig. 2.

Referring to said drawings, the number 1 indicates the stadias-sight, which is pivoted to a lug, 2, at the left-hand side of the barrel 3, 30 near or at the muzzle, but in such position on the under side of the barrel as not to interfere with the ordinary bayonet-stud, the said sight, by being hinged or pivoted to the under side of the barrel, hanging in a vertical position at one side, as in full lines, Fig. 1. The rear globe-sight, 4 or 5, is arranged at two and one-half or three feet distant from the sight 1, as may be convenient and suitable, and it is likewise arranged on the left-hand side of the 35 gun, either upon the bend of the stock 6 or near the breech end of the barrel, such a globe-sight consisting of a lateral projection or flange having a central orifice for the eye to look through.

The sight 1 is constructed on the principle 40 of the stadias-sight with a slot, 7 8, but differing therefrom in the respect that the usual stadias is a true angular opening, while in my invention the opening is not truly angular, but 45 the side 7 is uniformly curved from end to end, while the side 8 is perfectly straight, thereby constituting a variable opening. The open-

ing, as marked 100, 200, 300, 500, 700, and 900 yards, is calculated for the height of an infantry or cavalry soldier at the ranges alluded to, strictly in accordance with the required elevation of the muzzle in degrees and minutes requisite to enable the target or other object aimed at to be struck by the projectile at the different ranges indicated on the sight, 55 which is effected by the curved side 7 opposite the straight side 8 of the variable sight-opening.

A slide, 9, is arranged on the sight 1 so as to be adjusted thereon, and in practice the 60 stadias-sight is turned to a horizontal position, as shown by dotted lines, Fig. 1, looking at the target or object through the globe-sight 4 or 5 and the slot in the sight 1, after which the slide 9 is adjusted by sliding it until it indicates in the slot 7 8 that part of the slot which 65 exactly includes the height of the target or object aimed at. The slide being accurately adjusted, the sight 1 is turned back until it hangs vertically, after which aim is taken at 70 the target or object and the gun fired, when the projectile will reach the range indicated. This is due to the arrangement of the stadias-sight under the barrel adjacent to the muzzle 75 of the barrel, to enable the barrel to be proportionately elevated as the range is increased. Great steadiness of aim is also secured, for the reason that at any range used the eye of the person is always, when firing, at an invariable point—that is, the globe-sight 4 or 5, and 80 therefore the aim, is necessarily more certain and steady than in the strained position of the person using the elevated rear or ladder sight of the ordinary system. The combination and arrangement described being strictly 85 correlative for distance to the depression or elevation of the slide for increased or decreased range, the person has no occasion to estimate, calculate, or measure the distance of the target or object, nor necessity for the employment 90 of any proportionate or direct measure distance.

By my invention a recruit can be as easily taught the use of the stadias-sight as the most instructed officer, as my invention does not 95 necessarily involve a knowledge of numbers, length, or unit of measure.

Having thus described my invention, what I claim is—

1. The combination, with the barrel of a rifle or cannon, of the stadia-sight secured adjacent to the muzzle, and constructed with the variable opening formed by a straight side and a curved side, and a slide on said sight for indicating in the variable opening that part of the said opening which exactly includes the height of the object aimed at, together with the exact elevation of the muzzle required to strike the object, substantially as described.
2. The combination, with the barrel of a rifle or cannon, of the stadia-sight hinged adjacent to the muzzle, to be adjusted either to a horizontal or a vertical position, as described, and constructed with the variable opening formed by a straight side and a curved side, and a slide on said sight for indicating in the variable opening that part of the said opening which exactly includes the height of the object aimed at, together with the exact elevation of the muzzle required to strike the object, substantially as described.
3. The combination, with the barrel of a rifle or cannon, of a stadia-sight hinged adjacent to the muzzle, and constructed with an opening variable in width throughout its length, and a slide on said sight, whereby when the latter is turned to a horizontal position the adjustment of the slide will indicate in the variable opening that part of said opening which exactly includes the height of the object aimed at, and when the sight is turned downward to a vertical position the exact elevation of the muzzle will be indicated for striking the object, substantially as described.

In testimony whereof I have hereunto set my hand in the presence of two subscribing witnesses.

EDWARD L. BERTHOUD.
